CLAIM

The ornamental design for a bag support, as shown and described.

DESCRIPTION

FIG. 1 is a front right perspective view of a bag support exemplary of an embodiment of the design;

FIG. 2 is a left side view of the bag support of FIG. 1;

FIG. 3 is a right side view of the bag support of FIG. 1;

FIG. 4 is a rear view of the bag support of FIG. 1;

FIG. 5 is a front view of the bag support of FIG. 1;

FIG. 6 is a bottom view of the bag support of FIG. 1;

FIG. 7 is a top view of the bag support of FIG. 1;

FIG. 8 is a front right perspective view of the bag support of FIG. 1 holding a bag;

FIG. 9 is a front right perspective view of a bag support exemplary of another embodiment of the design;

FIG. 10 is a left side view of the bag support of FIG. 9;

FIG. 11 is a right side view of the bag support of FIG. 9;

FIG. 12 is a rear view of the bag support of FIG. 9;

FIG. 13 is a front view of the bag support of FIG. 9;

FIG. 14 is a bottom view of the bag support of FIG. 9;

FIG. 15 is a top view of the bag support of FIG. 9; and,

FIG. 16 is a front right side perspective view of the bag support of FIG. 9 holding a bag.

The broken line showing of a bag is included for the purpose of illustrating environment and forms no part of the claimed design.
